UNITED STATES PATENT OFFICE.

CHARLES ENGLER, OF AUSTIN, TEXAS.

COTTON-CHOPPER.

1,356,758.

Specification of Letters Patent. Patented Oct. 26, 1920.

Application filed May 7, 1919. Serial No. 295,294.

To all whom it may concern:

Be it known that I, CHARLES ENGLER, a citizen of the United States, residing at Austin, in the county of Travis and State 5 of Texas, have invented a new and useful Cotton-Chopper, of which the following is a specification.

This invention relates to improvements in cotton choppers, the object of the invention 10 being to provide an improved machine of this character which is capable of being steered by the feet of the driver to follow the line of the cotton drill and in which the chopper gear head can be raised and lowered 15 to suit the height of the team used in hauling the chopper carriage.

A further object of the invention is to provide a machine of the character set forth in which the speed of rotation of the chopper 20 may be changed at will, thereby to leave wider or narrower spaces between the cuts in the drills.

A further object of the present invention is to generally improve the construction of 25 machines of this character and to provide a machine that is comparatively simple in construction and highly efficient in operation.

With the foregoing and other objects in 30 view, which will appear as the description proceeds, the invention consists in the novel features of construction and combination of parts which will be more fully described hereinafter and particularly pointed out in 35 the claims.

In the drawings accompanying and forming part of this specification,

Figure 1 is a longitudinal section taken on the line 1—1 of Fig. 3, certain of the 40 parts being broken away;

Fig. 2 is a cross section taken on the line 2—2 of Fig. 3, looking in the direction of the arrows;

Fig. 3 is a plan view of the chopper mechanism and its carriage;

Fig. 4 is a longitudinal section taken on the line 4—4 of Fig. 3; and

Fig. 5 is a section taken on the line 5—5 of Fig. 3.

50 The same characters of reference designate the same parts in the different figures of the drawings.

Referring to the drawings, 50 designates a suitable frame mounted on an axle 4 having a pair of ground wheels 2 and 3. The axle is loosely mounted in one of the wheels,

for instance the wheel 2, while the wheel 3 is connected to the axle for rotation therewith by means of a key or spline, indicated in dotted lines at 5 in Fig. 3. Any other 60 preferred means for securing the axle 4 for rotation with the wheel may be used. A pair of depending hanger arms 6 provided with sleeve-formed upper ends 7 are loosely mounted on the axle 4. A gear head or 65 frame formed of upper and lower brackets 8 and 9 is adapted to be pivotally mounted in the lower ends of the arms 6. The brackets 8, 9 are secured at their ends to a pair of perforated blocks 10, through one of 70 which a pivot pin 11 passes, said pin also passing through an opening in the lower end of one of the arms 6 and being secured against longitudinal movement in the arm 75 by any suitable means, as for instance a nut 12 threaded on the end of the pin 11. The opposite side of the gear head is pivoted by means of a counter shaft 13 passing through the arm 6 and through the other perforated block 10, said counter shaft having a bearing at its opposite end in a third 80 depending arm 14 loosely mounted on the axle 4. A spur gear 15 is secured to the axle, and loosely mounted on the axle adjacent to the arm 14 is a fourth depending 85 arm 16 carrying at its lower end an intermediate gear 17 in mesh with the spur gear 15, said arm being provided with an L-shaped extension 18 having a slot in which a pin 19 carried by the arm 14 is adapted 90 to move. A spur gear 20 is secured to the counter shaft 13 in mesh with the intermediate gear 17. By this construction the intermediate gear can be raised or lowered to 95 permit different sizes of gears to be used on the counter shaft 13, thereby to change the speed of rotation of the shaft.

A bevel pinion 21 is secured to the inner end of the counter shaft within the gear frame 8, 9, and meshes with an idler bevel 100 gear 22 mounted for rotation on a vertical shaft 23 secured in the gear frame, said idler being in mesh with a bevel pinion 24 secured at the end of a shaft 25 that is journaled in a pair of bearing blocks 26 secured 105 between a pair of connecting straps 27, which are adapted to swing about the longitudinal axis of the shaft 23. It will thus be seen that when the ground wheel 3 rotates the axle rotates with it because of the 110 spline connection between the axle and wheel 3, and rotary motion is transmitted through

the train of gearing 15, 17 and 20 to the counter shaft 13 and thereby transmitted through the bevel pinion 21, idler gear 22 and bevel pinion 24 to the shaft 25.

5 An angular frame 28 is secured at its ends to opposite sides of the upper and lower connecting straps 27, this frame being so bent that the side 29 thereof is at an angle of approximately 30 degrees to the 10 ends of the straps 27. Secured to the side 29, within the frame, is an angular bracket 30 having an opening through which passes a stud shaft 31, the outer end of which is secured in an opening in the side 29. The 15 shaft 31 carries adjacent to its inner end a rotatably mounted spider formed of a central disk-shaped member or hub 32 having secured therein a plurality (shown herein as five in number) of radial arms 33, each having secured at its outer end a hoe or knife 34. A suitable spacing member or washer 35 is placed on the stud shaft between the bracket 30 and the hub 32 of the spider. A bevel gear 36 is secured to the hub 32 for 20 rotation therewith on the shaft 31, in mesh with a bevel gear 37 secured to the end of the shaft 25. It will thus be seen that the 25 rotary motion imparted to the shaft 25 as above described will cause the rotation of the spider and thereby the hoes or knives 34.

The frame 28 is supported by means of a pair of spring members 38 secured at one end to the frame, one at each side thereof, and at the opposite end to the frame 50 of the carriage, whereby the rotating hoes or knives 34 will normally be maintained in proper yielding contact with the ground.

For steering the chopper frame 28, a pair of uprights or standards 39 are secured to 40 the frame, one at each side thereof, each having a pedal 40 mounted on its upper end in position to be operated by the feet of the driver when seated on the seat 41, whereby said frame may be swung from one side 45 to the other for following the line of the cotton drill.

For raising the chopper out of the ground I provide a hand lever 42 mounted on the frame 50 of the carriage within reach of the 50 driver and connected by means of a rod or cable 43 with an eye bolt 44 carried by the upper strap member 27. A second lever 45 is mounted on the carriage frame and is connected by means of a rod or cable 46 with 55 an eye bolt 47 carried by the gear head 8, 9, whereby this gear head may be raised or lowered to change the angular position of the hoes 34 with relation to the ground. By this construction it is possible to regulate 60 the chopper to suit the height of the horses used to haul the carriage. This is to say, when very high horses are used the front of the carriage will be thrown upwardly and the rear downwardly, and if the gear head 65 were rigidly connected with the carriage

frame the hoes or knives 34 would be caused to sink too deeply into the ground. On the other hand, if very small horses were used the hoes would probably swing too high above the ground. By the present construction, however, this difficulty is entirely overcome, since when large horses are used the lever 45 may be shifted so as to raise the hoes sufficiently to compensate for the extra height of the horses, while when small horses 75 are used the lever may be shifted to lower the hoes. In Fig. 3 is shown broken away a pole or tongue 48 of the usual construction, attached by angular straps 49 to the frame 50 of the carriage and to which the team 80 may be hitched.

While I have described in detail the structure herein illustrated, it is to be understood that I do not thereby limit my invention to the precise features of construction shown, 85 as I am aware that many modifications and mechanical changes may be made therein without departing from the spirit and scope of the invention as set forth in the appended claims.

Having thus described my invention, what I claim is:

1. In a cotton chopper the combination with a wheel supported structure including an axle, arms hung from and adapted to swing relative to the axle, a gear supported by and movable with the arm, and means for transmitting motion to said gear from the axle, and a structure connected at one end to the arms, said structure being mounted for lateral angular adjustment relative to the arms, a longitudinal shaft carried by said structure, means for transmitting motion thereto from the gear, a rotary chopper actuated by said shaft, a yieldable support for the rear portion of the structure, and adjustable means for raising and lowering the front end of said structure.

2. The combination with a wheel supported structure including a drive axle, arms carried by and mounted to swing on the axle, a gear frame carried by the arms, a gear in said frame, and means for driving the gear from the axle, of a structure connected to the frame at one end and mounted to swing laterally relative thereto, a shaft journaled in said structure and driven by the gear, adjustable means connected to the gear frame for raising and lowering the structure at one end, adjustable means for raising and lowering the other end portion of the structure, a yielding support for one end portion of said structure, and a rotary chopping element actuated by the shaft.

3. In a cotton chopper the combination with a wheel supported structure including a drive axle, of arms carried by and mounted to swing on the axle, a structure connected at one end to said arms, adjustable means for raising and lowering the respective end por-

tions of said structure, a gear carried by one end of the structure, means for transmitting motion thereto from the axle, a longitudinal shaft in said structure and actuated by the gear, and a rotary chopping element actuated by and adjustable angularly relative to the shaft, said shaft carrying structure being bodily movable upwardly and downwardly relative to the axle and being

adjustable angularly laterally relative to the arms.

In testimony that I claim the foregoing as my own, I have hereto affixed my signature in the presence of two witnesses.

CHARLES ENGLER.
